ABSTRACT

The present invention discloses a crimping apparatus useful for crimping terminal contacts onto electrical wires and more particularly to improved indentors having an adjusting member whereby each indentor can be adjusted to insure equal depth penetration, and further disclosed is an improved funnel and funnel cam wherein the funnel is spring driven against a cam having a blocking portion, a funnel opening portion and a ramp portion operable to return the funnel to a closed position.

CRIMPING APPARATUS

BACKGROUND OF THE INVENTION

The art of crimping terminal contacts onto electrical wires or leads as such are known as in the art, is well developed as exemplified by U.S. Pat. No. 3,416,213 among many others. Generally speaking the crimping art includes the steps of placing a contact between crimping dies or indentors, inserting a prepared electrical lead into the barrel of the contact and crimping it firmly onto the lead. Where a hand-operated crimping apparatus is used, the depth of crimp can be controlled simply by the amount of pressure applied. Obviously, a hand tool of this type can crimp a rather large range of sizes of leads and terminals. However, where it is desired to automate the operation, the amount of crimp; i.e., the depth the dies or indentors advance, is not as versatile. This means then that an automatic or semiautomatic apparatus can be used for different lead and contact sizes by changing out the indentors and the mechanism driving such indentors.

Another problem workers in the field have experienced is the mechanism opening and closing the funnel which guides the leads into the contact barrels. Because the mechanism must be coordinated with the indentors, such mechanism as well as the funnel itself must be complex to achieve the desired results.

Accordingly the present invention provides, in a apparatus useful for crimping terminal contacts onto electrical leads, the apparatus, being of the type having a funnel assembly, for guiding the leads into the contact and also having a plurality of indentors operable to crimp the contact onto the lead, an improvement being first a funnel consisting of two halves, each half having a leg portion and on one end thereof semi-circular portion with a radiused tapered groove along its open side so that when the funnel halves are in abutting relation, the grooves cooperate to form a funnel opening, and each half further having on another end a perpendicular extending, cam following pin, and a spring retaining pin on the leg portion, and a pair of funnel cams each having a base portion, upstanding wall portion and a step-like cam portion having a angled wall surface adapted to block the afore-mentioned cam following pin whereby the funnel halves are kept in closed engagement with each other, a wall parallel to the funnel leg whereby the pin may move freely outwardly under biasing force of said springs thereby opening the funnels, and a ramp on the step whereby the pin may be returned to its abutting relation with the angled wall surface thereby bringing together the funnel halves; and secondly, a plurality of indentors where each indentor consists of a indenting head, a camming tail and a double ended bolt, each end being threaded and adapted to threadedly join the head to the tail and further adapted to vary the length of the indentor by adjusting the depth of penetration of the bolt in to the head and tail.

BRIEF DESCRIPTION OF THE DRAWINGS

FIG. 1 is a perspective view of the assembled crimping apparatus (incorporating the present invention);

FIG. 2 is an exploded view of the crimping head assembly adapted for use on the crimping apparatus of FIG. 1;

FIG. 2a is an enlarged view of a funnel cam;

FIG. 3 is a back view of the assembled crimping head assembly of FIG. 2;

FIG. 4 is a view in partial cross-section showing the mechanism driving the crimp head assembly of FIG. 2;

FIGS. 5 and 6 are front views of the crimping head assembly of FIG. 2 showing different operating positions;

FIG. 7 illustrates a carrier strip, terminal contacts and electrical leads utilized by the crimping apparatus in FIG. 1 and also the funnel assembly and indentors of FIG. 2.

DESCRIPTION OF THE PREFERRED EMBODIMENT

The crimping apparatus of FIG. 1 is adapted to crimp a terminal contact 10 as seen in FIG. 7 onto an electrical lead 12 to produce a terminated lead 14. So that this operation can be done on an assembly line basis, a plurality of contacts 10 are mounted on a carrier strip 16 which is fed through the apparatus. The strip, made of a plastic film such as MYLAR, consists of a base sheet 17 having spaced apart slots 18 along its rear side 19 and a narrow strip 20 electronically welded on top of the sheet and extending rearwardly from the front edge 21. Base sheet 17 and strip 20 form pockets 22 between the electronic welds which hold contacts 10.

The apparatus in FIG. 1 includes the mechanical apparatus 26 and its housing 28 which also doubles as a carrying case. The case includes a hinged side 29 which provides access to apparatus 26, a reel assembly 30 which includes a free wheeling feed reel 31 on which is coiled afore-mentioned carrier strip 16 loaded with contacts 10. The reel assembly 30 also includes a reel mounting spindle 32 and a vertical attachment post 33.

The apparatus 26 includes on its left side (toward the left margin) a wire stripper assembly 36 which has been disclosed in U.S. Pat. No. 3,630,105. As taught in that patent an end of an electrical lead 12 is inserted into a funnel shaped opening 37 and four blades (not shown) within the assembly cut away or strip a portion of insulation from lead 12 leaving a bare section of conductor 38 exposed as shown in FIG. 7. Besides opening 37, other parts of the stripper assembly 36 which is shown include the stripper head 39, an insulation scrap basket 40, and to the right, a stripping adjusting knob 41. A protective shield 42 encloses most of the assembly.

The crimping assembly 44 is on the right of apparatus 26 and includes the crimping head assembly 46 and the rocker assembly 48 (FIG. 4) and the belt feed 50. Additionally but not shown are the power means to drive both the wire stripper assembly 36 and crimping assembly 44.

A crimping head adjustment wheel 52 is located to the left and below the crimping head assembly.

The important aspect in the present invention is the crimping head assembly 46 which is shown in exploded fashion in FIG. 2 orientated in the position it occupies on the crimping assembly 44. Beginning with the face of the assembly 46, the first element is a clear plastic cover plate 53 which contains a plurality of mounting holes 54, a central aperture 55 and a horizontal slot 56 integral with the aperture.

The element behind cover 53 is indentor retainer ring 58 which contains a number of mounting holes 59 and on the rear side, two slots 60a, each 180° apart and which form a part of carrier strip slot 60 which can be seen in FIG. 3. The left hand slot 60a has one corner

designated at 62, rounded to permit belt 16 to move into the slots without snagging an edge.

The next part in the assembly 46 is the cam wheel 64. The front surface of wheel 64 contains two identical cam slots 65, each 180° apart. The slots are adapted to receive a funnel cam 66, held therein by funnel cam retainer 67 which is attached to wheel 64 via screw 68 threadedly engaging bore 69 in the slot. The construction of funnel cam 66 can best be seen in FIG. 2a. The cam includes a base member 70 and an upstanding wall member 71 integral with the base and having a zig-zag configuration. Further there is a cam member 72 integral with base 70 and wall portion 71, and contains a ramp 73.

The rear side (away from the reader) of cam wheel 64 contains two slots, 180° apart, which form another portion of carrier strip slot 60 and are designated at 60b. Also found on the rear side of wheel 64 are four indentor cam seats 73, each being 90° apart from its neighbor. Each seat receives an indentor cam 75 and a return cam 76. Cam wheel 64 also has a pin 77 which is housed in an appropriate aperture (not shown) and extends rearwardly from the wheel.

Indentor guide 80 of the crimping head assembly 46 is shown in FIG. 2 to the left of cam wheel 64. Guide 80, a metal disk, receives a split wire funnel assembly 81 in its funnel groove 82 located on its front side. The groove terminates in the center of the guide in a funnel bore 83 which extends therethrough. A wire removal slot 84 extends laterally of bore 83, both slot 84 and bore 83 being in alignment with slot 56 and aperture 55 respectively found on the plastic cover plate 53. Toward each lateral extremity of groove 82 is a recess slot 85 which receives a funnel spring 86 one end of which is attached to a pin (not shown) projecting rearwardly from a leg member 87 on funnel assembly 81 and which thereby biases each half of funnel 81 laterally away from funnel bore 83.

Each half of funnel 81 includes the afore-mentioned leg member 87 which terminates outwardly at a point 88 which contains a rearwardly projecting cam pin 89. Inwardly each leg member 87 terminates in a semi-circular portion 90 which is attached perpendicularly to the leg member. Each semi-circular portion has a tapered, radiused groove 90a extending inwardly from one side and a cylindrical radiused groove portion 90b extending to the opposite side.

The rear side of guide 80 can best be described by referring to FIG. 3 as well as FIG. 2.

Bisecting the guide 80 is portion 60c of carrier strip slot 60. Attention is drawn to the fact that the rearward opening of wire removal slot 84 terminates in a section of carrier strip slot 60.

Radiating outwardly from funnel bore 83 are four indentor grooves collectively numbered 92 and spaced 90 degrees apart from each other.

A rearwardly facing step 93 encircling the perimeter of guide 80 on its rear side, as can be seen more clearly in FIG. 2, receives the inwardly extending end of return cam 76.

A plurality of bores 94 extend through guide 80 for mounting purposes.

Each indentor groove 92 receives an indentor 96 (FIG. 2) which consists of three sections; i.e., an indenting head member 97, a tail camming member 98 and an adjusting connecting member 99 which both connects the two and adjusts the overall length. Al-

though not shown, the member is threaded at either end and is received in threaded apertures located in the two outer sections. Head member 97 terminates in a tapered, squared-off point 100. Tail member 98 has its lower surface; i.e., the side away from the reader in FIG. 2, notched at 101 so that the indentor can move freely under cam return 76 as seen in FIG. 3. At the outside end of the tail section a pin 102 projects up from the floor of the notched area to a height equal to the step 103 formed by reason of notching.

A rear cover plate 104 covers the rear top half of crimping head assembly 46. Holes 105 therein admit conventional bolts (not shown) for purposes of mounting the plate to the assembly.

The assembly of crimping head assembly involves telescoping the three main elements into each other so that guide 80 fits within cam wheel 64 and those two elements fit within ring 56. The assembly is fixed to the crimping apparatus so that the guide 80 and ring 56 are stationary and the cam wheel is free to rotate a distance equal to the length of a slot 106 in cam return 76.

The back of an assembled crimping head assembly 46 is shown in FIG. 3 so as to illustrate the interrelationship of the indentors 96 with the several other elements of the assembly. Each tail member 98 abuts the beveled side 105 of cam 75 and pin 102 projects into slot 106 in cam 76. As cam wheel 64 is oscillated back and forth, indentors 96 are driven in and out along grooves 92 via the cooperating structure of the two cams 75 and 76. Connecting member 99 insures that each indentor 96 travels inwardly to the same depth as the other indentors 96.

FIG. 4 illustrates the rocker assembly 48 which oscillates cam wheel 64. Rocker arm 110 is rocked back and forth by conventional means; i.e., an electric motor (not shown) driving a fly wheel 111 on which a roller 112 is mounted and which rides in slot 113 in arm 110. Arm 110 pivots about a pin 114 and is connected to pin 77 in cam wheel 64 via slot 115 located in the upper end of the arm. A switch 116 controlling the operation of rocker arm 110 is seen to the right of roller 112. The assembly which drives carrier strip 16 through the carrier strip slot 60 is seen in part in phantom and consists of a pair of drive wheels (not shown) and belt 116 on which are fixed a plurality of teeth 117 which engage slots 18 in carrier strip 16.

FIG. 5 shows the front of crimping head assembly 46 and the relation between funnel assembly 81 and funnel cam 66. The pin 89 on each leg 87 engages cam 66 at or near the point of juncture 120 between wall portion 71 and cam member 72 thereby holding each funnel half 81 in the closed position shown.

Referring now to FIG. 6, cam wheel 64 has been rotated counter-clockwise allowing cam member 72 to move past pin 89 and out of blocking position of funnel assembly 81. Under the force of springs 86 the funnel halves are pushed open as seen. As cam wheel 64 rotates back, pin 89 rides up ramp 73 and back into the blocked position seen in FIG. 5.

OPERATION OF THE PREFERRED EMBODIMENT

The operator selects an insulated electrical lead 12 and inserts it into wire stripper assembly 36 and causes the four blades therein (not shown) to accurately sever a length of insulation therefrom to expose a section of conductor 38. He moves the stripped lead to the closed funnel halves (FIG. 6) and inserts it therein, and into

the barrel 125 of contact 10 positioned immediately behind. The operator actuates a switch (not shown) which causes the rocker assembly to rotate cam wheel 80 clockwise a distance far enough to cause pin 89 to ride along the front of ramp 73 keeping the funnel halves closed and maintaining correct alignment of lead 12 and contact 10. Concurrently the indentors 75 are causing indentors 86 to advance inwardly to crimp barrel 125 onto lead 12. Subsequent thereto cam wheel 64 is rotated counter-clockwise which causes indentors 96 to move outwardly and the funnels halves to open. Simultaneously carrier strip 16 is advanced (via belt 116) to the right so that a new contact 26 is placed between indentors 96 and aligned with grooves 91. Additionally the now terminated lead 14 is advanced along wire removal slot 84 where lead 14 and contact 10 are pulled from carrier strip 16. This completes the cycle and leaves the crimping head assembly 46 in readiness for terminating another lead 12.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

What is claimed is:

1. In an apparatus useful for crimping terminal contacts onto electrical leads, the apparatus being of the type having a funnel assembly for guiding and holding the leads into the contact and having a plurality of indentors for crimping the contact onto the lead, an improvement comprising:

- a. a funnel assembly consisting of two halves, each half having a leg portion, a perpendicular, semi-circular portion having a radiused groove, with a tapered section on one end of said leg portion, said grooves cooperating to form a funnel opening 40 when said halves are in abutting relation, and a cam pin on another end of said leg portion, and further having a spring engaging pin on said leg portion;
- b. a pair of funnel cams each having a base member, an upstanding wall member and a cam member, 45 said cam member including a funnel blocking portion adapted to block outwardly movement of said cam pin on said funnel leg portion,
- a parallel portion adapted to permit outwardly 50

movement of said cam pin, and a ramp adapted to return said cam pin from said parallel portion to said funnel-blocking portion; and

c. a plurality of indentors each indentor consisting of a indenting head, a camming tail and a connecting member threadedly engaged both to said head and said tail and operable to vary the length of said indentor by adjusting the amount of threaded engagement of either or both of said head and said tail thereonto.

2. In an apparatus useful for crimping terminal contacts onto electrical leads, an improvement comprising:

- a. center portions with a funnel opening extending inwardly from one side and merging with a cylindrical opening extending to the other side, said center portion split along a plane extending through the axis of said funnel and cylindrical openings thereby forming two identical center portion halves;
- b. a pair of leg members each extending laterally from one of said center portion halves and attached thereto, and
- c. a camming pin on a free end of each of said leg members;
- d. a pair of biasing means each adapted to bias a center portion half away from another center portion half; and
- e. camming means adapted to engage said camming pin on said leg member for camming said center portion halves into abutting engagement with each other.

3. The camming means of claim 1 further including blocking means thereon adapted to keep said center halves in abutting engagement and ramp means 35 thereon adapted to return said camming pin to said blocking means.

4. In an apparatus useful for crimping terminal contacts onto electrical leads, an improvement comprising:

- a. a plurality of indentors, each indentor having a indentor head member, one end being tapered and another end having a threaded aperture;
- b. a cam-engaging tail member having on one end a threaded aperture; and
- c. a connecting member threaded on both ends and adapted to be attached to said head and tail members via said threaded apertures and further adapted to vary the length of said indentor by adjusting the depth of said threaded attachment.
